UNITED STATES PATENT OFFICE.

WILLIAM J. HOSCEIT, OF CHICAGO, ILLINOIS, ASSIGNOR TO NATIONAL DUMP CAR COMPANY, OF CHICAGO, ILLINOIS, A CORPORATION OF MAINE.

RAILWAY-CAR CONSTRUCTION.

1,411,275.

Specification of Letters Patent.

Patented Apr. 4, 1922.

Application filed August 21, 1920. Serial No. 405,024.

To all whom it may concern:

Be it known that I, WILLIAM J. HOSCEIT, a citizen of the United States, residing at Chicago, in the county of Cook and State 5 of Illinois, have invented certain new and useful Improvements in Railway-Car Constructions, of which the following is a specification.

This invention relates to railway car construction, and more particularly to a railway car floor construction.

It is common practice to unload cars by use of clam-shell buckets, this being true even when cars are provided with floor dump doors, it being appreciated that it is not always desirable to dump the lading of cars in certain spots. It has been found that these clam-shell buckets in closing, while taking a load, sometimes, and not infrequently, grip the cover plates over the intermediate cross sills and center sills and distort or tear same away from their proper places.

The object of this invention is to prevent this objectionable occurrence, and to provide simple and efficient means adjacent said cover plates to guide the gripping points or edges of such buckets in a manner to clear the cover plates.

This and other objects are accomplished by means of the arrangement disclosed on the accompanying sheet of drawing, in which—

Figure 1 is a transverse sectional view of a railway car including a floor structure embodying my invention;

Figure 2 is a top plan view of a railway car floor dump door embodying my invention;

Figure 3 is a sectional view of the same door taken in the plane of line 3—3 of Figure 2; and,

Figure 4 is a detail sectional view of the floor structure, including a cross sill, cover plate thereover, and the door, embodying my invention, to prevent gripping of the cover plate, the parts being shown on an enlarged scale.

The various novel features of my invention will be apparent from the following description and drawings and will be particularly pointed out in the appended claims.

Referring to the figures of the drawings, it will be noted that I have disclosed my in-

vention in connection with a dump car, including a body having sides 10 and ends 11 carried by an underframe including cross sills 12 and a center sill 13. As is customary, the cross sills and center sills are covered by cover plates 14 and 15, respectively, which cooperate with dump doors 16 preferably pivotally mounted at their inner ends 17 to the center sill structure and swung downwardly and inwardly for dumping purposes. When in closed position the edges of the doors underlie the cover plates 14 and 15.

As mentioned hereinabove, when unloading the car by means of clam-shell buckets, it sometimes happens that the gripping edges of the bucket as it is being closed in taking a load, grip the cover plates and either distort same or tear them partially or wholly away from their proper positions. To prevent this occurrence, I have provided means adjacent said cover plates for preventing a gripping member passing into engagement with said cover plates. In this particular instance, wherein the floor includes dump doors 16, I have provided the dump doors with upwardly extending ribs or corrugations 18 and 19 adjacent the cover plates 14 over the cross sills and cover plates 15 over the center sills, respectively, said ribs or corrugations extending lengthwise along said cover plates and being so positioned with respect thereto that any gripping engagement that said buckets might have had on the cover plates is entirely prevented. These ribs act as guide means operative upon the gripping points or edges of such buckets, positively directing the latter away from said cover plates, thereby preventing said cover plates from being torn from their positions or distorted in any manner whatsoever.

It is my intention to cover all modifications of the invention falling within the spirit and scope of the following claims.

I claim:

1. In a railway car, a floor portion including a cover plate, and means adjacent said cover plate for positively directing a gripping member away from gripping engagement therewith.

2. In a railway car, a floor portion including a cover plate, and means extending lengthwise along the edges of said cover plate for positively directing a gripping

member away from gripping engagement therewith.

3. In a railway car, a floor portion including a cover plate, and a floor door associated therewith and having means for positively directing a gripping member away from gripping engagement with said cover plate.

4. In a railway car, the combination of

cross sills and a center sill, cover plates over 10 said sills, and a floor door having upwardly projecting ribs arranged adjacent the edges of said cover plates for positively directing a gripping member away from gripping engagement therewith.

Signed at Chicago, Illinois, this 18th day of August, 1920.

WILLIAM J. HOSCEIT.
